UNITED STATES PATENT OFFICE.

CHARLES S. ASH, OF ROYAL OAK, MICHIGAN.

METHOD OF FORMING RIMS FOR WIRE WHEELS.

Application filed October 4, 1924. Serial No. 741,524.

The present invention relates to a method of producing wire wheel rims having spoke nipple seats, in which method the rims are held to the desired diameter, contraction in diameter due to spoke lacing strains is reduced to a minimum by a re-conditioning of the metal, and distortion of the rim during the punching operation is obviated, thereby eliminating uncertainty in wire wheel manufacture, obviating the necessity for oversize stock rims, insuring accuracy in rim diameter of the finished wheel, facilitating and cheapening manufacture and assembly, and securing greater tire efficiency and providing 10 interchangeability. The present method also includes a sizing operation wherein the rim, after the operation of forming the spoke nipple seats therein, may be reconditioned to eliminate initial strains due to the 15 rolling operation in forming the stock rim, and reduce to the minimum, the contraction in diameter of the rim under the strain put thereon in lacing and truing the wheel.

With the above and other ends in view, the 20 invention consists in the method of forming wire wheel rims, which method includes contracting the rim to densify the metal and prevent undue contraction under spoke lacing strains and also holding the rim to the 25 proper size in diameter and against distortion, during the operating of forming the nipple seats therein, and then forming said 30 seats while the rim is so held, whereby the operation of forming said seats will not distort the rim or reduce it in diameter and such seat 35 forming operation performed while the rim is held, imparts a set to the metal which prevents subsequent distortion or contraction due to strain set up in the metal during the seat 40 forming operation.

The invention further consists in including in such method, the reconditioning of the rim after the seat forming operation to relieve the rim from strains set up in the metal and 45 thus reduces to the minimum, the reduction in rim diameter due to the strain put thereon by the spoke lacing when the wheel is assembled and further consists in certain other new and useful features all as hereinafter more fully 50 described and particularly set forth in the appended claims, reference being had to the accompanying drawings, in which:

Figure 1 is a side elevation of a punch press shown in outline, with a rim holder in place thereon and shown in elevation, as illustrating suitable mechanism which may be em-

ployed in carrying out the present method and is illustrative of one means for the purpose which may be employed;

Fig. 2 is a front elevation of the device 60 shown in Fig. 1;

Fig. 3 is a vertical axial section of the same;

Fig. 4 is an enlarged cross sectional view of a slightly modified construction of rim holder and of rim sizer for use in connection therewith, and

Fig. 5 is a plan view of the device shown in Fig. 4.

In practicing the present method, any suitable means may be employed to hold the rim during the punching operation and limit the rim to a certain fixed diameter.

As illustrative of one method which may be employed in holding the rim, an expanding holder or block is illustrated in the accompanying drawings and this holder is so constructed as to adapt it for use upon an ordinary punch press to facilitate the operation of punching or forming the semi-spherical depressions in the rim forming seats for the spoke nipples. It is obvious that in the practice of the present method, any suitable means for holding the rim and limiting it to a certain fixed diameter may be employed 80 and that the punching or forming of the seats for the spoke nipples may be performed in any convenient manner other than that shown, the employment of the punch press shown, being merely illustrative of an instrumentality which may be employed for the purpose.

In the accompanying drawing the holder which is designated as a whole by the numeral 1, is shown as comprising a series of rim segments 2 each formed upon its outer face 3 to conform exactly to the configuration of the inner surface of the wheel rim 4 which is to be seated thereon by placing the rim thereover and then moving these segments outwardly to expand the holder and limit the rim to the exact diameter desired. These segments 2 are mounted in suitable ways 5 upon a supporting body or hub member 6 so that they may be conveniently moved outwardly or radially by means of a conical-shaped expanding nut 7 having screw-threaded engagement with a cylindrical portion 8 of the hub, said nut having an outer inclined face 9 to engage inner similarly inclined faces 10 on the segments 2. The supporting member or hub 6 is formed hollow to receive the horn

10 of the punch press 11 so that the entire holder 1 may be conveniently mounted upon the horn directly beneath the punch or punches 12 carried by the ram of the punch 5 press. These punches have suitably formed ends to properly form the cup-shaped or semi-spherical depressions in the rims 4 which depressions are provided to form seats for the nipples of the wire spokes when the 10 wheel is assembled. The expanding nut 7 may be rotated in any suitable manner to move it inwardly upon the cylindrical portion 8 of its support and forces the segments 2 outwardly within the rim 4 and any suitable means such as springs 13 may be employed to move the segments inwardly when the nut is retracted. The inward movement of this nut is preferably limited in any suitable manner (not shown) so that the rim 15 mounted thereon cannot be contracted by the punching operation to a diameter which is less than the desired diameter of the finished rim. Should a stock rim be used which is of less diameter than the diameter for which the holder is set when the expanding nut has 20 fully expanded the segments to the proper diameter, such rim will be expanded to the desired diameter and the operation of punching the rim while it is so held, will give a set to the metal which is in expanded condition, so that the rim will not contract of itself when removed from the holder but will have the exact desired diameter, and further, the 25 punching of the rim while it is held to shape laterally of the rim by the holder gives a set to the metal which prevents the rim from 30 springing out of true when released.

If a stock rim be employed which is of 40 slightly greater diameter than the desired diameter of the finished rim, then the punching operation which is performed upon the rim while mounted upon the holder, the holder forming a die for the punches, said rim will be contracted by the punching operation 45 to the desired diameter, closely fitting the expanded holder which is limited in its expansion to a diameter which will give the desired diameter to the finished rim.

Obviously the arrangement may be such 50 that one or more punches may be employed to punch the rims and the holder may be rotatively mounted upon the punch press so that the rim may be conveniently rotated beneath the punches, such rotation being performed by hand or by any suitable mechanical 55 means (not shown) which may operate in timed relation to the movements of the punches. Likewise the expanding of the holder may be effected in any suitable manner, either by the hand operated nut as shown, or by suitable mechanical means mechanically operated by power.

Stock rims are formed from hot rolled strip steel or hot rolled mill-section stock. 60 This hot rolling process tends to lengthen or

stretch the stock and in the process of manufacturing the stock rim a cold rolling operation is usually employed which again tends to lengthen or stretch the stock and leaves the stock rim under initial strains. Such 70 rims are satisfactory for compression wheels such as disk or wood wheels for the reason that the rim is further stretched in the same direction by the mounting of it upon the disk or wood spokes which are placed under compression thereby. In a suspension or wire wheel the rim is subjected to strains put thereon by a tensioning of the wire spokes between the hub and rim and therefore this strain tends to contact the rim and, due to the 80 conditions of the metal of the rim by reason of the methods employed in its manufacture, the rim is more susceptible to such strains and may be unduly contracted by the pull of the spokes, and the rim may continue to 85 shrink in diameter after the wheel is in service, causing reduction in spoke tension or even causing the spokes to become loose. It is therefore important that this condition of the metal be changed or its effect counteracted, 90 and this is accomplished in the present method by holding the rim to the desired diameter, and while so held, performing the punching operation which imparts a set to the metal and counteracts this tendency of 95 the metal to contract under the strain imposed upon the rim by the spokes.

It is obvious that the stock rim may be first contracted to recondition the metal, and then punched, these operations serving to 100 give a set to the metal and should a stock rim be employed which is slightly under size, such rim may be stretched or expanded and then punched, the punching operation serving to recondition the metal by contracting 105 it and also to give a set to the metal so that the rim will not change in diameter from that to which it has been previously expanded.

The punching operation tends to shrink the rim but in certain instances it may be found desirable to further recondition the metal by further contracting the rim. This reconditioning operation is particularly desirable where the rim is formed from stock which is comparatively soft, as the further reduction in diameter of the rim renders the metal more compact, hardens it slightly and leaves the rim in a condition to withstand the strains to which it is subjected in a suspension wheel. 110

This reconditioning operation may be performed by removing the holder 1 from the punch press and while the rim is in place upon the holder with the segments 2 slightly retracted, perform the sizing operation by 115 bringing a heavy inward force against the periphery of the rim to contract it to the exact desired diameter. Any suitable means for reconditioning or sizing of the rim may be employed but as illustrative of suitable 120

means for the purpose, an arrangement of mechanism is shown in Figs. 4 and 5 wherein an internal chuck or holder similar in construction to the holder 1 is provided for engaging within the rim 4 and a series of ring segments 14 are arranged around the rim to engage the exterior surface thereof, said ring segments being slidable radially inward upon guides 15 provided therefor upon a suitable support carried by the hub member 6. To force these ring segments 14 radially inward against the outer surface of the rim, a beveled ring 16 is provided with an inclined surface 17 to engage like inclined surfaces on the outer sides of the segments 14 and thus by forcing the ring 16 laterally of said segments, the segments 14 are forced radially inward to contact the rim 4. This inward movement of the segments 14 is preferably limited in any suitable manner so that the external diameter of the rim 4 will be of the exact dimension desired and all rims produced will be of the exact desired size and all distortion of the rim will be eliminated, thus greatly aiding in the assembly of the wheels as well as practically eliminating the contraction of the rim in the assembled wheel under the inward pull of the spokes thereon. Further, rims thus formed will remain, in use, in the condition in which they are put by the operations performed in the present method and this final sizing operation will also insure a finished rim of the exact diameter desired.

Obviously any suitable means may be employed for performing this final sizing operation and the contraction of the segments 14 by the movement of the wedge ring 16 may be effected by any suitable power means applied in any suitable manner to the wedge ring, or to the means employed for moving the segments radially.

Having thus fully described my invention, what I claim is:—

1. The method of forming wire wheel rims having spoke nipple seats, which method consists in limiting contraction of a rim substantially throughout its entire inner circumference and forming said seats in the rim inwardly thereof while said rim is so limited to impart a set thereto.

2. The method of forming wire wheel rims having depressions forming spoke nipple seats, which method consists in holding a rim interiorly and limiting contraction thereof substantially throughout its entire internal circumference, and forming depressions in the rim inwardly thereof to provide said seats while the rim is so held and limited and to impart a set to the rim.

3. The method of forming wire wheel rims having seats for spoke heads, which method consists in inserting within a stock rim a holder of an external diameter substantially equal to the desired internal diameter of the finished rim to be engaged by said rim sub-

stantially throughout the entire internal circumference of said rim, and then imparting a set to the rim by depressing portions thereof inwardly of the rim while said rim is in place upon said holder.

4. The method of forming wire wheel rims having semi-spherical seats for spoke heads, which method consists in expanding a holder within a stock rim to a diameter equal to the desired diameter of the finished rim, and then forming said seats in the rim by a punching operation performed exteriorly of the rim with said holder forming the die and means for limiting contraction of the rim.

5. The method of forming wire wheel rims having seats for spoke heads, which method consists in contracting a rim to a desired diameter to compress the metal and forming said seats in the rim while in its contracted condition, whereby a set is imparted to the metal to prevent contraction of the rim under spoke lacing strains.

6. The method of forming wire wheel rims having seats for spoke heads, which method consists in limiting contraction of a stock rim substantially throughout its entire internal circumference to a desired diameter, forming depressions in said rim inwardly thereof while the rim is so limited to impart a set to the rim, and then re-conditioning the rim to relieve the metal from initial strains imposed by said previous operations.

7. The method of forming wheel rims which consists in depressing inwardly, portions of the rim thereby contracting the rim and imparting a set thereto, and then forming the rim to the desired rim diameter prior to spoke assembly.

8. The method of forming wheel rims having depressions forming seats for spokes, which consists in forming and holding a stock rim to a desired diameter and then forming said depressions in the rim inwardly thereof while so held to impart a set thereto.

9. The method of forming wheel rims which consists in forming a stock rim to a desired diameter, then forming portions of the rim inwardly to impart a set to the metal, and finally contracting the rim to the desired rim diameter to prevent contraction thereof under spoke lacing strains.

10. The method of forming wire wheel rims having seats for spoke heads, which method consists in holding a stock rim and limiting contraction thereof substantially throughout its entire internal circumference, forming portions of said rim inwardly while said rim is so held and limited to impart a set to the metal, and then contracting the rim to the exact diameter desired for the finished rim prior to spoke assembly.

In testimony whereof I affix my signature.
CHARLES S. ASH.
